UNITED STATES PATENT OFFICE.

THOMAS CHARITY, OF BURLINGTON, KANSAS.

DESIGN FOR A CULTIVATOR-SHOVEL.

SPECIFICATION forming part of Design No. 33,053, dated August 7, 1900.

Application filed July 13, 1900. Serial No. 23,550. Term of patent 14 years.

To all whom it may concern:

Be it known that I, THOMAS CHARITY, a citizen of the United States, residing at Burlington, in the county of Coffey and State of Kansas, have invented and produced a new and useful Design for a Cultivator-Shovel, of which the following is a specification.

Figure 1 is a perspective view of a cultivator-shovel, showing my new design. Fig. 2 is a top plan view thereof. Fig. 3 is a bottom plan view thereof.

As shown in the drawings, my design consists of an angular cultivator-shovel having a long point 1 and an inclined ridge 2, extending from the point to the center of the shank 3, said shank extending upwardly in a gradual curve from the upper line of the ridge to its terminal end and the blades 4 of the shovel diverging laterally from the point to their rear ends at an acute angle, the side walls of said blades being inclined and the outer rear corners of said blades being curled upward

at 5. The rear edge of each blade 4 is slightly curved from its upper line to the point at which the curled corner starts an acute curvature and continues to its terminal end. The shank 3 presents its curved surface centrally to the point 1 and has an enlargement at its upper end. The bottom edges 6 of the blades are substantially straight from the point 1 to the curved corners 5, and all parts of the shovel are of substantially-equal thickness throughout.

Having thus fully described my new design, what I claim is—

The design for a cultivator-shovel, substantially as shown and described.

In testimony whereof I have hereunto set my hand in presence of two subscribing witnesses.

THOMAS CHARITY.
